CLAIM

The ornamental design for a dual stud construction toy block, as shown and described.

DESCRIPTION

FIG. 1 is a top perspective view of a dual stud construction toy block according to the invention;
 FIG. 2 is a bottom perspective view thereof;
 FIG. 3 is a top plan view thereof;
 FIG. 4 is a bottom plan view thereof;
 FIG. 5 is a side elevational view thereof, the opposite side elevational view being identical; and,
 FIG. 6 is an end elevational view thereof, the opposite end elevational view being identical.
